SIGN

Clifford Walton, Buffalo, N. Y.

Application February 9, 1950; Serial No. 143,271

3 Claims (Cl. 40—125)

1

This invention relates to signs, advertising devices and the like, and particularly to such devices as are adapted to attract the attention of observers by movement or animation of some portion thereof.

It is an object of the invention to provide a sign, advertising device, or the like, in which eye-attracting motion of elements of the sign will be obtained without the application of mechanical or electrical energy.

It is another object of the invention to provide a sign or the like in which movable elements carried by the sign are operated by air currents.

A further object of the invention is to provide a sign or the like in which air-current operated movable elements are arranged in such manner as to give the appearance of forming the sign.

Still another object of the invention is to provide a sign or the like having elements movable by air-currents which may be easily and inexpensively constructed, but which is durable and adapted for a wide variety of uses.

Additional objects of the invention will be apparent from the following specification taken in conjunction with the drawings, in which:

Figure 1 is a plan view of a sign constructed in accordance with the present invention, the sign representing a letter and having air-current operated movable elements mounted thereon.

Figure 2 is an enlarged vertical sectional view on line 2—2 of Figure 1 which illustrates the manner in which the air-current operated movable elements are mounted.

Figure 3 is a fragmentary vertical sectional view on line 3—3 of Figure 2.

Figure 4 is a further enlarged fragmentary sectional view similar to Figure 2, which shows in greater detail the bearings provided for the air-current operated movable elements.

Figure 5 is a fragmentary view of a sign similar to that in Figure 1, with the movable elements removed and the mounting screws shown in section.

Referring to the drawings, the numeral 10 is applied to the base or backing of a sign constructed in accordance with the present invention. The bases 10 may be formed in any desired shape or configuration, either as letters, designs, or combinations thereof. While it is evident that signs embodying the present invention may be constructed to present a number of angularly disposed faces to view, the present description will be limited to a sign in which a single base or backing 10 is used.

The base 10 may be formed of any suitable material in any desired or conventional manner, due regard being had for such factors as the required structural strength, resistance to abrasion, and the atmospheric conditions under which it will be used, etc. For most purposes, the bases may conveniently be formed of sheet metal or sheet plastic by a pressing or stamping operation, although, of course, wood, metal castings, molded plastics, and other materials may be used if desired.

Adjustably mounted at closely spaced intervals on the base 10 along the edges thereof and extending outwardly therefrom are a plurality of supports or posts 11. The posts 11 which can be of plastic, metal or other suitable material are secured to the base 10 by screws 12 which are inserted from the rear side of the base 10 through slots 13 and 14 and threadedly engaged in an offset enlarged portion 15 formed at one end of the supporting posts 11.

Each of the supports 11 is provided adjacent its other end with a transverse bore 18. A bearing housing 19 is carried in each of the bores 18. Each housing 19 comprises a cup which preferably is inserted and held in one of the bores 18 by pressing it therein, although other suitable methods of mounting may be used. At the bottom of the inside of each of the cups there is provided a bearing 22. The bearing 22 is preferably formed of molded glass and is provided on one face with a smooth rounded cavity 23. The washer 21 and the bearing 22 are firmly held in position in the cup with the cavity 23 facing outwardly by a retaining ring 24. The latter is screw-threadedly engaged with the interior of said cup adjacent the outer end thereof. The bearings 22 are thus mounted so as to permit their replacement if necessary.

The movable elements or rotors 28 provided by the present invention are, as shown in the drawings, screw-like in construction. Each of the rotors 28 comprises a body portion 29 which is generally cylindrical in shape and a plurality of integrally formed screw-like or volute-shaped splines or vanes 30 preferably extending the length thereof. The height of each of the splines or vanes 30 preferably increases from one end of the body 29 to the opposite end thereof so that the rotors 28 give the general impression of being conical in shape.

At each end of the body 29 of each of the rotors 28, there is provided a shaft 32. The shafts 32 each comprise a cylindrical needle-like portion of small diameter 33 at one end and an

enlarged portion at the other end having a threaded extension 34 which is removably engaged in an axially disposed threaded bore in one end of the body 29.

In assembling a sign constructed in accordance with the present invention, a base or backing 10 of desired shape is provided and bored or punched to provide the two series of mounting slots 13 and 14 therein. The oppositely disposed slots 13 and 14 which are associated with each pair of supports 11 are disposed perpendicularly to each other. Moreover, as will be seen most clearly in Figure 5, each of the slots 13 on the outer edges of a curved character is preferably formed with its longer dimension substantially normal to the outer curved edge. The slots 14 which are provided adjacent the inner edges of curved characters are preferably formed so that the shorter dimension of each is substantially normal to the curve of the inside edge of the characters.

The supports 11 are secured to the base 10 by means of screws 12 in opposing slots 13 and 14, with the cavities 23 in the bearings 22 of each pair of supports being aligned, each with the other. A washer 36 is provided for each of the screws 12 on the rear face of the base 10. While the supports 11 are still loose on the base 10, one of the rotors 28 is placed in position between each opposed pair of supports with the needle-like shaft ends 33 within the cavities 23 of the bearings. Subsequent tightening of the screws 12 so as to firmly hold the supports 11 in position results in the secure mounting of the rotors 28. The anti-friction bearings 22 serve as supporting bearings as well as thrust bearings for the shafts 32 and thus provide mountings which have a very small amount of friction and permit free rotation of the rotors 28.

Slots 13 and 14 are provided in the base 10 instead of cylindrical holes to permit lateral adjustment of the supports 11 at one end of each of the rotors so that suitable spacing of the rotors on signs or characters with curved or irregular outlines may be secured. Thus, while the location of the slots determines the general arrangement of the rotors 28, movement of the supports 11 within the limits permitted by the slots makes possible minor changes in position which may add to the eye-appeal of the sign. Such adjustment will, of course, be made before the final tightening of the screws 12 which hold the supports 11 in position on the base 10.

The rotors 28 are preferably formed of light-weight material such, for example, as plastics, from which they may be readily molded. Their shape with the multiple spline or vane arrangement is such that they will be rotated by even very small air currents. In thus rotating, the rotors 28 will reflect light and attract attention to the sign, advertising device, or the like. The rotors 28 may be of any desired color or finish and the base or backing 10 may, if desired, be colored the same or may be given a contrasting or harmonizing color.

It will be understood that the rotors 28 may be closely mounted on individual characters as described above and shown in the accompanying drawings or they may be disposed in any other desired arrangement, such, for example, as groups in the form of letters or designs on a large base or backing either with or without the letters or designs being otherwise indicated as by painting or other representation on the base behind the rotors. Furthermore, if desired, the base may be

cut out to form skeleton characters or designs.

Signs, constructed in accordance with the present invention, are adapted for use in a large number of applications. The eye-attracting motion of the rotors under even very light air currents makes them valuable for use as outdoor signs. Indoor signs embodying the rotors of the present invention may be so positioned as to cause spinning of the rotors by currents of ventilating air or, if desired, the rotors may be actuated by the air currents from a small fan.

While in many locations there will be sufficient light falling upon the sign to obtain an attractive effect even at night by the operation of the rotors, additional illumination can be provided, if desired, either from behind the sign, in which case the base or backing may be translucent, or from the front, as by a spot or flood light suitably placed. The spinning of the rotors 28 and the reflection of light therefrom which may be of different colors depending upon the color of the rotors, will produce a very interesting and attention-attracting sign.

It will be evident that the size of the rotors may be varied within wide limits. In some instances, the use of a large number of small rotors may be desirable. In other instances, a fewer number of large rotors may be preferred or a combination of large and small rotors may be used. The rotors shown in the accompanying drawings are provided with two splines or vanes. If desired, however, three, four, or even more splines may be provided on the rotors.

I claim as my invention:

1. A letter for an outdoor sign, comprising a base having the outline of said letter, a plurality of pairs of aligned bearings fast to said base and arranged along the opposite marginal portions of said base, said pairs of bearings being spaced along said marginal portions to substantially completely outline said letter, and the spacing of said pairs of bearings being substantially closer than the spacing of the bearings of each pair, a rotor having its opposite ends journaled in each pair of said bearings and screw-like splines projecting from said rotor a sufficient distance to rotate said rotors through motion derived from outside air currents.

2. A letter for an outdoor sign, comprising a metal base having the outline of said letter, a plurality of pairs of aligned bearing blocks fast to the front face of said base and projecting forwardly therefrom along the opposite marginal portions of said base, a cup bearing carried by each of said bearing blocks and opposing the cup bearing of the companion bearing block, said pairs of bearing blocks being spaced along said marginal portions to substantially completely outline said letter, and the spacing of said pairs of bearing blocks from one another being substantially closer than the spacing of the bearing blocks of each pair, a rotor having axial projections at its ends and journaled in the cup bearings of each pair of said bearing blocks, and screw-like splines projecting from said rotor a sufficient distance to rotate said rotors through motion derived for outside air currents.

3. A curved letter for an outdoor sign having an inside curved marginal portion generally parallel with and of shorter length than a corresponding outside marginal portion of said letter, comprising a base having the outline of said letter, a plurality of pairs of aligned bearings fast to said base with one group of bearings of said pairs being spaced a relatively large distance

from one another along said outside marginal portion of said letter and with the other group of bearings of said pairs being spaced a relatively small distance from one another along said shorter inside marginal portion of said letter, and said bearings substantially completely outlining said letter, and the spacing of said pairs of bearings being substantially closer than the spacing of the bearings of each pair, a rotor having its opposite ends journalled in each pair of said bearings, and screw-like splines projecting from said rotor a sufficient distance to rotate said rotors through motion derived from outside air currents, said splines being of progressively diminishing diameter from one end of said 15 rotor to the other with the ends of said rotors having splines of larger diameter being arranged

along said outside marginal portion of said letter, said splined rotors being in closely spaced massed relation to present a visually obstructed area greater than the visual free area between said rotors.

CLIFFORD WALTON.
